The ornamental design for the angled bottle, as shown and described.

DESCRIPTION

FIG. 1 is a perspective view of a first angled bottle showing my new design;

FIG. 2 is a perspective view of the angled bottle, opposite the view shown in FIG. 1, and illustrating the cap removed; FIG. 3 is a side elevational view of the angled bottle of FIG. 1 with the side opposite identical to the side shown; FIG. 4 is a top view of the angled bottle of FIG. 1; FIG. 5 is a bottom view of the angled bottle of FIG. 1; FIG. 6 is a perspective view of a second, smaller version angled bottle showing my new design; FIG. 7 is a side elevational view of the angled bottle of FIG. 6, illustrating the cap removed; and,

FIG. 8 is a side elevational view of the angled bottle, opposite the view shown in FIG. 7, but the cap is not removed.
